UNITED STATES PATENT OFFICE

JOHN W. HANEY, OF SPOKANE, WASHINGTON

BILLBOARD

Application filed December 24, 1928. Serial No. 328,096.

My present invention relates to improvements in bill boards which while adapted for various uses are especially designed for posting theatrical bills and advertising other enterprises, commodities and articles. As is well known the customary mode of affixing the bills or posters to the boards is to paste the successive strips composing the bill, (or a single sheet may sometimes be used) on the face of the board. After a number of these bills or sheets have been pasted one over another on the face of the board, it becomes necessary to remove the several layers of the old bills. This is usually done by first moistening the pasted bills, and then they are scraped from the board.

After one or more bills have been pasted upon the face of the board, difficulty is encountered in affixing new sheets or bills on the old bills, and the removal of these old bills by moistening and scraping, requires the expenditure of time and labor, together with additional expense.

By the utilization of the bill board of my invention these objectionable difficulties are obviated and the board is arranged so that one bill may quickly be affixed thereto and present a smooth and workman like finish, and when the necessity arises for removal of a bill and its replacement by a fresh one, this operation may be accomplished with facility and convenience.

The invention consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have so far devised for the practical application of the principles of my invention.

Figure 1 is a perspective view of a bill board embodying my invention illustrating one adhesive strip attached to the board, it being understood that a plurality of these horizontally extending adhesive strips are used for posting the bills on the board. Figure 2 is a top plan view at the left end of the

board of Figure 1. Figure 3 is a view in elevation at the top of the left end of Figure 1. Figure 4 is an enlarged detail end elevation showing the operating handle for the rock bars of the device, and the locking means for these rock bars. Figure 5 is a sectional detail view at line 5—5 of Figure 1. Figure 6 is an enlarged detail sectional view at line 6—6 of Figure 1.

In carrying out my invention I employ a rectangular board which is of suitable size and adapted to receive the standard sizes of bills or posters, and this board is provided at its ends with rigid supporting posts 2, 2. At the back of the board I arrange a plurality of horizontally extending rock bars 3, here shown as pipes, and these rock bars are journaled in bearings 4 spaced apart and located at the opposite ends of the board, and secured thereto by bolts as 5. I have shown four of the rock bars in Figure 1, but it will be understood that a greater or lesser number of these bars may be employed depending upon the size of the bill board, and upon the dimensions of the poster or bill to be affixed to the board.

These rock bars are designed to oscillate in their bearings and at one end each bar is provided with a rock arm 6 which has a collar 6' slipped over the end of the board, and a cotter pin 7 is used to secure the collar and its arm to the rock bar. At their front ends these rock arms are pivoted to a connecting bar 8 as indicated at 9, and it will be apparent that the connecting bar stands in a vertical plane along side of the posts 2 as seen in Figure 1. The lowermost rock arm is provided with a crank handle 10, and it will be evident that by moving this crank handle all of the rock bars may simultaneously be rocked on their axes.

At the lower end of the connecting rod a hinged extension 11 is provided and which is slotted to form a hasp to fit over a complementary staple 12 secured in the outer face of a post 2. By means of a padlock 13 slipped through the staple after the hasp is locked in proper position, the connecting rod together with the rock arms and rock bars may all be locked against movement. Of

course, the key for the lock is in the hands of a person authorized to use the bill board and the connecting bar is released before the bill board can be used.

5 Each of the rock bars is provided with a plurality of angular pins or hooks 14 which have shanks 14' and nuts 15 on the threaded ends of these shanks. The shanks are passed through holes 16 in the board and these threaded shanks are threaded through openings in the rock bar and clamped by the nut 15. The pin portion 14 stands in upright position in front of the face of the board as indicated in Figure 1, and the hole or slot 16 is of sufficient size to permit a slight movement of the angular pins when the bars 3 are rocked. At the rear of the board a weatherer strip or shield 17 is provided for each of the rock bars and this strip or shield is secured to the board above each of the rock bars to prevent entrance of moisture, snow or ice between the bars and the board, and to protect the bars from the weather.

In Figure 1 it will be seen that the angular pins 14 are arranged in horizontal rows extending from end to end of the board. Behind each row of pins an adhesive strip 18 is to be clamped. This adhesive strip is provided with an adhesive on one side only and this particular side becomes the outside or front face of the adhesive strip when it is placed in position. Assuming that four adhesive strips 18 are to be employed, the crank handle 10 is swung to the right in Figure 4 and this movement swings the pins 14 slightly away from the front face of the board 1. An adhesive strip similar to the strip 18 in Figure 1 is now slipped behind each row of pins 14, and the handle 10 is swung to the left. The movement of the handle 10 causes the various rows of pins to clamp the four strips between the pins and the face of the board. These four strips now present the adhesive face to which the single sheet poster or the strip bill may be attached. The adhesive face of each strip 18 may be moistened in suitable manner so that the strips will adhere thereto and the strips or the single sheet, are affixed on the face of the board by the usual operations, except that of course the bill or poster is not gummed or provided with paste.

For the purpose of holding the opposite ends of the bill or poster against the face of the board I provide a pair of clamp bars 19 located at the ends of the board and disposed in vertical position. At its lower end each bar is secured or anchored to the board by a staple 20 and at its upper end the clamp bar has an outwardly turned horn or lug 21. A spring hook 22 is provided for each of these outwardly turned ends of the clamp bars, and the spring hook is secured to the board by means of a bolt as 23. After the poster or bill has been affixed to the adhesive strips 18

these two clamp bars 19 are laid up against the opposite ends of the bill or poster and then by means of the spring hooks 22 the clamp bars 19 are drawn into frictional engagement with the opposite ends of the bill or poster and the latter is held against displacement by the wind or other element.

When the bill or poster is to be removed for replacement by a fresh one, or for other reason, the clamp bars 19 are first disengaged, then the padlock 13 is removed and the hasp 11 is released so that the crank handle 10 may be turned to the right. This movement of the crank handle swings all of the hooks 14 away from the face of the board, so that the entire bill or poster may be lifted or removed in one piece from the face of the board. Another poster may be affixed to the board by the operation previously described.

Having thus fully described my invention, what I claim as new and desire to secure by Letters Patent is:

1. The combination with a bill board having horizontal rows of openings of a plurality of rock bars journaled at the rear of the board, retaining pins carried by the rock bars and movable in said openings, and means for operating the rock bars whereby adhesive strips may be retained by the pins.

2. The combination with a bill board having rows of horizontal openings therein of a plurality of rock bars at the rear of the bill board, a connecting rod for said bars and means for operating said rod, and angular shaped hooks carried by said bars and movable in said openings for retaining adhesive strips against the face of the board.

3. The combination with a bill board having rows of openings therethrough of a plurality of rock bars journaled at the rear of the board, angular shaped pins carried by the bars and movable in the openings to clamp an adhesive strip, rock arms on the rock bars, a connecting rod for the rock arms, and an operating crank for said connecting rod.

In testimony whereof I affix my signature.
JOHN W. HANEY.
